UNITED STATES PATENT OFFICE.

EMANUEL F. SELZ, OF CHICAGO, ILLINOIS.

SHOE.

1,333,737.

Specification of Letters Patent. Patented Mar. 16, 1920.

Application filed November 5, 1917. Serial No. 200,234.

To all whom it may concern:

Be it known that I, EMANUEL F. SELZ, a citizen of the United States, residing at Chicago, in the county of Cook and State 5 of Illinois, have invented certain new and useful Improvements in Shoes, of which the following is a specification.

In walking, the great toe "grasps" the ground, exercising its natural prehensile function, and by this action tends to arch the inside of the foot and to roll the outer portion downwardly and inwardly. The outer portion of the foot, from the heel to the little toe, and the portion extending 15 across the toes to the great toe and inner ball of the foot are therefore the portions that normally sustain the weight of the body. In a yielding surface these portions of the sole of the foot would therefore sink 20 somewhat below the level of the portions on the opposite, inner side, and the position of the foot in such a bed or footing is anatomically the normal and natural one. In the conventional form of footwear now 25 in use, however, the vamp or upper clamps the stiff and unyielding sole, which is of uniform thickness and broader than the foot, flat against the sole of the foot, in which position it would naturally stand in- 30 clined somewhat upwardly from the outer toward the inner side, were it not forced by the weight of the body to a horizontal position when the wearer stands or walks; the result being that the foot is caused 35 to roll more or less over on to its inner side, into an abnormal position. The strain which is thus thrown on the inner arch by the weight of the body weakens it, and sooner or later is apt to cause it to break 40 or fall, producing the condition known as broken or fallen arches. Whether resulting in actual physical deformation or not, the strain is a frequent source of pain and irritation of a serious character.

Attempts have been made heretofore to construct footwear which will prevent or relieve flat feet or broken arches, usually by the provision of an artificial support along the underside of the inner arch, as 45 by a heel long on the inside, a long counter or stiffening which extends throughout the shank almost to the bunion joint, or by a metal or leather plate more or less accurately conformed to the contour of the inner 50 shank of the foot. My present invention, on the contrary, is based primarily on the

idea of relieving the inner arch by throwing the weight of the body as much as possible on the outside arch. The object of my invention, therefore, is the production of a 60 shoe of such form and construction as to cause the weight of the body to be more largely thrown upon the outside arch of the foot, correspondingly relieving the inside arch and affording a more natural and 65 anatomically correct position of the foot; which will enable the foot to describe its natural movements and function properly in walking; which dispenses with artificial rigid and uncomfortable supports; and 70 which will present as graceful and slightly an appearance as ordinary styles of shoes. My invention consists in the contour, shape and design of the different portions of my novel and improved shoe, the essential elements of the same being pointed out in the 75 appended claims.

In the drawings Figure 1 is a horizontal section of a left-foot shoe embodying my invention immediately above the sole thereof 80 and on the line 1—1 of Fig. 2; Fig. 2 is a cross-section on the line 2—2 of Fig. 1 and Fig. 3 (shown for purposes of comparison, a corresponding section of a shoe of ordinary construction; Fig. 4 is a cross- 85 section on the line 4—4 of Fig. 1 and Fig. 5 a corresponding cross-section of a shoe of ordinary form; Fig. 6 is a cross-section on the line 6—6 of Fig. 1 and Fig. 7 a corresponding section of an ordinary shoe; 90 Fig. 8 is a view of the innerside of a left-foot last formed for the construction of my new shoe; Fig. 9 a bottom plan view of the same; and Figs. 10, 11, 12, 13 and 14 cross sections on the line 10—10, 11—11, 12—12, 95 13—13 and 14—14, respectively, of Fig. 8.

The same reference characters indicate the same parts on all the figures of the drawings.

Referring first to Figs. 8 to 14, which 100 illustrate a last formed for the construction of my improved shoe, it will be seen that as compared with a last of ordinary and usual form,—the outline of which is indicated in dotted lines in Figs. 10 to 14,—the bottom of 105 the last is built up on the outside, beginning at the little toe and extending through the shank on the outside to a point about even with the middle of the heel, forming a curved longitudinal protuberance or swell 110 indicated on Fig. 9 by the shaded area 1. The inside of the last is cut away, beginning

slightly at the middle of the back of the heel and increasing until the cutting away becomes quite marked at the inner corner of the heel. The bottom surface of the last is, preferably, though not necessarily, slightly convex, which in the shoe results in the formation of a shallow socket or seat for the heel, this socket being somewhat inclined from the horizontal and highest on the inner side at the front of the heel. Forwardly of the heel the last is hollowed out more than usual on the inside of the shank, the hollow extending well up to the inner ball. The portions of the last cut away are indicated by the stippled area 2. The portion 3 shown in Fig. 9 is not prominent, as in certain lasts already known, and may protrude either slightly or not at all from the adjacent bottom surface. It results from these variations that as a whole the inner portion of the last, especially at the forward portion of the arch and diminishing rearwardly, is cut away more deeply than is usual, and the opposite or outer side is more prominent than in the ordinary last.

By means of a last modeled as above described my improved shoe is made according to well-known methods of manufacture, by lasting the insole 5, upper 6, lining 7, and welt 8, snugly to the last, stitching them together, filling the space within the sewing rib 9 of the insole and intermediate such insole and the outer sole 10 with a suitable filler 11, and securing the outer sole to the welt in the usual manner. In lasting the shoe the insole of course is made to conform accurately to the contour of the last and the effect of building up the outside of the last is to form a depression or pocket 12 along the outside edge of the shoe, into which the foot may sink. The thickness of the filler 11 varies to compensate for the depression and provide a uniformly curved seat upon which the outer sole 13 of ordinary form is seated.

The effect of cutting away the inside of the heel of the last as described is to elevate the forward inner side of the heel of the shoe, near the front of the heel seat, more than usual, the elevated area (marked 14) affording support vertically up the median line of the leg tending to some extent to restrain the heel from sliding forwardly in the shoe, and also acting to tilt or roll the foot into the depression or pocket along the outer edge. As shown in the drawings (compare Figs. 2 and 3) the heel 15 is higher from its horizontal base on the inner side of the shoe than the outer side, to support the sole of this portion of the shoe in the inclined position which is given it by the cutting away of the inside and the building up of the outside of the bottom of

the last. However, the same effect may be secured by making the heel of uniform height and using a properly shaped wedge inserted under the insole on the inside of the shoe. Forwardly of the heel and at the forward part of the inside arch, the insole 5 and outer sole 10 are cut away well up toward the ball of the foot, and the upper 6 correspondingly extended downwardly under and around the inner under portion of the instep—see Fig. 4—thus incidentally affording a slight but flexible support thereto.

It is evident that in a shoe thus constructed the foot will seat itself in its normal anatomical position, and as far as may be will function just as it would if unshod. The shoe will have no tendency to roll the foot inwardly down on to the inside arch, twisting the angle to an unnatural position and giving a sidewise wrench to the metatarsal arch and imposing an excessive strain on the inner portion thereof, resulting in serious painful disorders or deformation of the foot, such as are inherent in footwear of ordinary and usual construction.

I claim:

1. A shoe having the upper surface of the inner sole formed with a depression extending along and adjacent the outer edge thereof, said depression being confined substantially to the outer portion of the sole, and the inner portion of the sole in the region of the ball of the great toe being raised with respect to said depression and substantially horizontal.

2. A shoe the inner surface of the sole of which is formed near the outer edge thereof with a concave depression limited to the outer portion of the sole and merging near the toe, into a substantially flat portion which receives the toes and the ball of the great toe.

3. A shoe the surface of the sole of which is provided with a raised portion substantially at the inside front portion of the heel with a concave depression extending along the outer edge of the sole and a substantially horizontal portion at the inside portion higher than said depressed portion and upon which the ball of the great toe rests.

4. A shoe the surface of the sole of which is provided with a raised portion substantially at the inside front portion of the heel and with a raised shank merging into said raised portion at the inside of the heel and with a concave depression extending along the outer edge of the sole and a substantially horizontal portion at the inside portion higher than said depressed portion and upon which the ball of the great toe rests.

EMANUEL F. SELZ.
